UNITED STATES PATENT OFFICE.

LEVI DEDERICK, OF ALBANY, NEW YORK.

IMPROVEMENT IN THE MODE OF TIGHTENING AND SECURING THE KEYS OF THE JOURNAL-BOXES OF CONNECTING-RODS OR PITMEN.

Specification forming part of Letters Patent No. **19,548**, dated March 9, 1858.

To all whom it may concern:

Be it known that I, LEVI DEDERICK, of Albany, in the county of Albany and State of New York, have invented a new and Improved Method of Tightening and Securing the Keys of the Journal-Boxes of Connecting-Rods or Pitmen; and I do hereby declare that the following is a full, clear, and exact description of the same, reference being had to the accompanying drawings, forming part of this specification, in which—

Figures 1 and 2 are respectively a side view and front view of a pitman having my invention applied in different ways to the two journal-boxes, Fig. 1 representing one of the journal-boxes partly in section.

Similar letters of reference indicate corresponding parts in both figures.

This invention consists in the application of springs to the tightening-keys of the journal-boxes of connecting-rods and pitmen in such a manner that the said springs will drive up the keys to tighten up the boxes as fast as required by the wear of the boxes and journals, and hold the keys in their places to retain the proper degree of tightness of the boxes.

To enable others to put my invention in practice, I will proceed to describe the ways of applying it and its operation.

A is the pitman, having its stub ends respectively indicated by *a* and *a'*. *b* and *b'* are the journals. *c d* and *c' d'* are the linings of the boxes which fit the journals. *e* and *f* are the straps, and *f* and *f'* the bolts which confine the straps. All the above-mentioned parts are constructed and applied in the usual manner.

The upper journal-box is represented as having the key *g* applied in the most common manner—viz., passing through two slots in the strap, and between the stub end *a* and lining-piece *c* in a direction transverse to the axis

of the journal. This key is turned down to a cylindrical form at the smaller extremity, and has cut upon it a screw-thread, to which is fitted a nut, *i*, and between this nut and the strap is applied the spring *h*, which constitutes my invention. This spring is spiral and coiled round the key, and by its pressure against the nut it exerts a constant tendency to draw in the key and tighten up the lining-pieces *c d* upon the journal, and consequently when the pressure of the journal is thrown upon the piece *d*, and the piece *c* is relieved, if there is any slackness in the box the spring draws in the key and tightens it. The spring also at all times prevents the key working back and allowing the box to get loose.

The lower box is represented as having the key *g'* applied between the stub end *a'* and lining-piece *b'* in a direction parallel with the journal. The spring *g'*, applied to this key, is a plate-spring, and is secured by a screw or other means to that side of the stub end *a'* on which is the head of the key, on which it presses constantly, so as to prevent the key drawing out and as to drive it farther in to tighten up the box, whenever necessary, when the pressure of the journal is on the lining-piece *d'* and the piece *c'* is relieved.

Either of the above ways of applying the spring and key may be applied to either or both of the journal-boxes of a connecting-rod or pitman.

What I claim as my invention, and desire to secure by Letters Patent, is—

The application of springs to act upon the tightening-keys of the journal-boxes of connecting-rods and pitmen, substantially as and for the purpose herein specified.

LEVI DEDERICK.
